UNITED STATES PATENT OFFICE.

JAMES T. DENTON, OF DANBURY, CONNECTICUT.

WOOL-PULLING DEVICE.

Application filed March 23, 1926. Serial No. 96,704.

This invention relates to a device for pulling fleece from sheep skins and the like. At present the common practice is to treat these skins with a depilatory to destroy or loosen 5 the roots of the fleece and then to pull it from the hide or skin by hand. This is a slow tedious operation and when finished the fleece is mixed up with the fibres running in all directions. Furthermore, there seems 10 to be an opinion that the depilatory is injurious to the hide and the fleece.

It is, therefore, an object of the present invention to provide a mechanical device which may be operated either by hand or 15 power to pull the fleece from the hide or skins and which will perform this operation without previously treating the skin with a depilatory.

It is also an object of the invention to 20 provide a device of this character which will not only pull the fleece from the skin but will partially card it so that the fibres lie more or less in a parallel relation, thus reducing the carding operation required.

25 With the foregoing and other objects in view, I have devised the device, two arrangements of which, are shown in the accompanying drawing, similar reference characters being employed throughout the various figures to indicate corresponding elements. In this drawing,

Fig. 1 is a side elevation showing a device constructed according to my invention, the showing being somewhat diagrammatical.

35 Fig. 2 is a detail transverse section substantially on line 2—2 of Fig. 1.

Fig. 3 is a section of the work roll on an enlarged scale to indicate the construction thereof, and

40 Fig. 4 is a view similar to Fig. 1 of a somewhat different arrangement but also shown diagrammatically.

I have found that by providing the surface of a cylindrical roll with a large number 45 of small teeth undercut or inclined in the direction of rotation of the roll, if this roll is given a relative rotation adjacent the wool side of a sheep skin these teeth will first act to lay the fibres in more or less parallel relation and that they will then wrap themselves about the roll, as shown at (F') in Fig. 1, and further rotation of the roll or a relative lateral movement thereof will pull the fleece from the skin. This 55 roll may be of any suitable material, for example, a cylindrical piece of steel with the

teeth cut in the surface and then hardened, or a roll of suitable material may be covered with a shark skin arranged so that the fine teeth of this skin are all inclined in one direction and located in planes extending transversely to the axis of the roll. As indicated in Figs. 1 and 3, I have found that such a roll if used as indicated above, will first lay out the members of the fleece in substantially parallel relation and will cause them to wrap themselves onto the surface of the roll, and will then pull them away and separate them from the skin. This effect may be secured by hand, that is, 60 the roll is supported on a suitable holding means which is projected from its opposite ends and can be gripped by the operator. The skin may be clamped taut on a suitable support and then the operator may take the 65 roll and by giving it a combined rotary and bodily movement over the fleece side of the skin it can pull this fleece from the skin.

It is, however, preferred to operate the roll by power and provide mechanical means 70 associated therewith to present the skin with the fleece to the surface of the roll. I have shown in Fig. 1 somewhat diagrammatically an arrangement of devices for this purpose. In this figure, 10 is the work roll which may 75 be rotated at the proper speed by any suitable means, not shown, the direction of rotation being indicated by the arrow, and the surface of this roll is provided with small inclined teeth 11 inclined to point in the direction of rotation. These teeth, as indicated above, 80 may be formed by cutting them on the surface of a steel roll and then hardening or they may be provided by fastening a shark skin to the surface of the roll by any suitable means, such as cement. The diameter 85 of the roll should be sufficient so that the circumference is, say, two or three times greater than the length of the fleece (F) 90 to be removed to facilitate stripping of the fleece from the roll. For this purpose I provide a stripper roll 12 covered with stripper cloth having fine bristles or bristle-like wires 13, and this is rotated so that its surface speed is greater than that of the working roll and in the same direction so that the teeth 11 will catch the rear ends of the 95 fleece on the work roll and strip it from the surface of this roll in the direction in which the teeth 11 on the work roll are inclined. 100 The fleece may then be stripped from the stripper roll by stripping means, such as the

vibrating wires 14, which may be vibrated by means of a roll 15 running in a toothed-wheel 16, the stripped fleece being deposited on a conveyor belt 17 by which it may be carried to any desired location.

To secure best results and to prevent injury to the surface of the skin by the work roll it should be held taut on a suitable support while it is being moved past the surface of this roll. In Fig. 1 is shown a pair of feed rolls 18 to the rear of the work roll 10, and these rolls are geared to rotate together by spur gears 19. In order to secure a firm grip on the skin 20 the surfaces of these rolls are provided with longitudinally extending grooves and ribs 21 which intermesh in proper spaced relation as the rolls are rotated and draw the skin past the working roll. I also provide a supporting roll 22 over which the skin passes and which holds it in proper spaced relation from the surface of the working roll. The skin is held taut by a suitable means on the other side of the roll. In Fig. 1, I have shown a slowly rotating drum 23 on which the skin may be clamped by a suitable means, as for instance, the clamps 24. I have shown only a few of these clamps, it being understood that these clamps are mounted on the opposite ends of the drum and are substantially equally spaced throughout the circumference of the drum. In the form shown they comprise brackets 25 secured to the drum to which the clamps are pivoted, and the clamps each have a rounded extension 26 to engage the top surface of the skin and clamp it to the surface of the drum under the action of the spring 27. The skin is stretched on the surface of the drum and clamped thereto by these clamps, and as the drum rotates and the skin is drawn over the supporting roll 22 adjacent the surface of the work roll 10 by means of the feed rolls 18, the drum and these clamps will hold the skin taut, the driving connections for the feed rolls and the drum being so proportioned that the surfaces of the feed rolls tend to move slightly faster than the surface of the drum. As the clamps move to the point where the skin separates from the drum they engage a stationary cam 28 which swings them outwardly to release the skin and allow it to separate from the drum.

In Fig. 4, I have shown a slightly different arrangement in which instead of using the clamps 24 I use a roll 29 which presses on the top side of the skin and holds it onto the surface of the drum 23, the drum and this roll being held back so as to keep the skin taut.

It is to be understood that the arrangement of the devices for presenting the skin to the work roll are merely illustrative as other arrangements may be provided for performing this operation. It will be ob-

vious that this device will remove the fleece from the skin much faster than it can be done by the old hand method. As there may be plenty of power used it is not necessary to use a depilatory to loosen the fleece in the skin. Furthermore, as the fibres of the fleece are first more or less carded and laid in a substantially parallel relation before they are pulled from the skin they are laid in more or less parallel relation on the conveyor 17 and they are, therefore, partially carded, and the vegetable matter is loosened so that the fibres are easily cleaned.

Having thus set forth the nature of my invention, what I claim is:

1. A device for removing fleece from skins which comprises a rotatable roll having a large number of fine teeth in its surface inclined in the direction of rotation arranged to grip the fleece and pull it from the skin without cutting it.

2. In a device for removing fleece from skins, a rotatable roll having fine teeth in its surface inclined in the direction of rotation, a support for the skin to be treated, and means causing a relative bodily movement between the skin and the roll, said teeth being arranged to grip the fleece and by relative movement with the skin to pull the fleece from the skin.

3. In a device for removing fleece from skins, a rotatable roll having fine teeth in its surface inclined in the direction of rotation, and means for presenting the skin to the roll in position for the fleece to be engaged and removed by said teeth, said teeth being arranged to grip the fibres of the fleece and by relative movement with the skin to pull the fleece from the skin.

4. In a device for removing fleece from skins, a rotatable work roll provided with fine teeth on its surface inclined in the direction of rotation, means for holding the skin and presenting the fleece side to the roll, and a stripping roll on the opposite side of the roll to remove the fleece from said roll.

5. In a device for removing fleece from skins, a rotatable work roll provided with fine teeth on its surface inclined in the direction of rotation, a movable support adjacent one side of the roll, a guide roll adjacent the work roll in position to hold the skin adjacent said roll, feed rolls to the rear of the work roll arranged to draw the skin between said rolls, and means cooperating with the support to retain the skin taut as it is moved past the work roll.

6. A device for removing fleece from skins which comprises a cylindrical roll provided with a large number of fine teeth on its surface inclined to said surface and in planes transverse to the axis of the roll, said roll being supported for rotation to give relative movement between the roll and skin, and said teeth being arranged to grip the fleece

and by relative movement with the skin to pull the fleece from the skin.

7. In a device for removing fleece from skins, a rotatable work roll provided with fine teeth on its surface inclined in the direction of rotation, a movable support adjacent one side of the roll, a guide roll adjacent the work roll in position to hold the skin adjacent said roll, means for feeding

the skin between said guide roll and the work roll, and a stripper roll at one side of the work roll rotated with a surface speed greater than that of the work roll and moving in the same direction as the adjacent surface of said roll. 15

In testimony whereof I affix my signature.

JAMES T. DENTON.
